ADDING AND RECORDING MACHINE.

1,198,821.

Specification of Letters Patent. Patented Sept. 19, 1916.

Application filed March 9, 1914. Serial No. 823,455.

To all whom it may concern:

Be it known that I, LEE S. BURRIDGE, a citizen of the United States, and a resident of the borough of Manhattan, city, county, and State of New York, have invented certain new and useful Improvements in Adding and Recording Machines, of which the following is a specification.

This invention relates to the same type of machine as disclosed in the application filed by me April 5, 1913, bearing the Serial Number 759,231, with such improvements and modifications as will appear.

Figure 1 is a plan view of the machine; Fig. 1^a is a detail of the ribbon shift lock; Fig. 2 is the side elevation of the machine, with one of the side plates omitted so as to better show the parts within the frame; Fig. 2^a is a cross section of one of the key bars and racks; Fig. 3 is a detail side elevation of the mechanism for raising and lowering the adding wheels and other details; Fig. 4 is a detail front elevation of the adding wheel shaft and mechanism for returning to zero; Fig. 5 is a detail of the locking mechanism for the zero handle; Fig. 6 is a sectional detail plan view of a trip carrying mechanism and its relation to the adding wheels; Fig. 7 is a sectional side elevation of the parts in Fig. 6; Fig. 7^a is a cross section of Fig. 7; Fig. 8 is a side elevation of the locking mechanism for the operating handle in connection with the zero returning mechanism; Fig. 9 is a detail side view of the mechanism operated by the zero handle; Fig. 10 is an enlarged detail front view of the shutter in co-operation with type bars; Fig. 10^a is a side view of the lower part thereof in connection with the rock shaft.

The frame of the machine has a top or supporting board 100 inclined forward and downward and provided with parallel slots 100^a from front to rear (Fig. 1). These slots serve to receive the sliding key bars 101 which are provided with longitudinal grooves 101^a, as seen in Fig. 2^a, and these grooves receive the key bar 101 and guide it in its sliding action. Each key bar carries a number plate 102 formed with depressions, as shown best in Fig. 2, so as to be engaged readily by the operator's fingers. This plate is rigidly mounted on the key bar and may be made of cel-

luloid and is numbered in each depression from 0 to 9, the zero being at the lower or forward end. On the under side of each key bar 101, a rack bar 103 is mounted by means of studs 103^a, seen in Figs. 2 and 2^a, which pass through the rack bar and secure the rack bar to the key bar. The plate 102 may have an upward projection at its rear end 102^a to facilitate the manual return of the key bar. The rack bar is formed of right angled sheet metal, the horizontal portion being mounted on the key bar, as seen in Fig. 2^a, and the downwardly depending portion has gear teeth cut therein, and at the upper or rear extremity a downwardly depending lug 103^d of greater length than the gear teeth is provided with slot 103^e, Fig. 2.

The slot 103^e is to receive the shouldered stud 104 provided on the upper extremity of a bell lever 104 fulcrumed on the frame 75 of the machine at 104^a, and having a shorter rearwardly extending arm 104^b provided close to its rear extremity with a shouldered stud 104^d extending through slot 105^a provided at the lower end of the type bar 105, 80 mounted to slide vertically in a comb 106, Figs. 1 and 2, provided with notches for the several type bars in their upper extremity. The stationary pin 107 extends through the longitudinal slots 105^b of all the type bars 85 and assists in guiding the type bars, yet allows them to swing on said pin as a pivot in a transverse direction, so that the type bars may move slightly rearward (away from the bottoms of the notches in the comb 90 106 and to the left in Fig. 1) so that the type 105^c provided on the rear side and upper end of each type bar may be moved toward a platen 108, journaled at 108^a, on the C-shaped side frames 109, secured at the 95 lower ends to the frame of the machine. Paper is supplied to the platen from the roll 111 supported on the C-shaped frames and is pressed against the platen by feed roller 110 mounted on the right angled frame 112 100 journaled at 112^a on the front portion of the frame of the machine and caused to bear against the platen by the compression spring 110^b which can be released from pressure for straightening the paper by means of 105 the upwardly projecting handle 112^b (Fig. 2). It will be noted that the paper is fed between the platen 108 and feed roller 110

and that instead of a narrow roll of paper, a wide sheet can be employed by passing it in the open space 113 left by reason of the C-shape of the frames supporting the platen 5 and may project to any extent at either side of the machine, thereby enabling the insertion of paper of any desired width.

Each type bar 105 carries ten number or digit types 105^c arranged consecutively from 10 0 to 9 with the zeros at the upper ends of the type bars and they are normally held away from the platen by spring pressed rollers 114 (Fig. 2), mounted on the ends of arms 114^a, journaled on the pin 107, one such 15 arm being situated between each type bar and its adjacent one, there being as many rolls 114 as there are type bars. A spring 114^b for each arm 114^a secured at its upper end to a stationary shelf of the frame of the 20 machine tends to pull up this end of the arm and apply pressure in a downward and rearward direction by means of the roller 114 upon the rear of the type bar 105, Fig. 2. When a key bar 101, by means of the 25 plate 102, is moved down from the normal position shown in Figs. 1 and 2, the corresponding type bar 105 will be raised to bring that type 105^c into printing line opposite to the platen which agrees with the 30 figure or number of the plate 102 appearing immediately above a frame plate 115, under which the key bars 101 disappear when moved down. The upper edge forming the 35 pressure bar of this plate 115 is bent upwardly at 115^a at an angle to form a convenient stop for the operator's finger when moving the key bar downward. The pressure bar 115^a may be separate from the plate 115 and adjustably connected therewith by 40 slotted lugs 115^b on said bar slidable on screws 115^c in plate 115, to suit the fingers of different operators, see Figs. 1 and 2. The disposition is such that when the key bar is moved down, the digit appearing immediately above the plate 115, the type bar 45 will be raised so that the same corresponding type digit will have been brought to the printing line. As long as no other part of the machine is operated, the key bars 101 50 may be moved freely and independently of each other downward from the normal position and upward in case any error has been made in setting up an item which will appear in a reading line directly above the plate 115. At the right hand portion of the 55 machine is located the main operating handle 116 (at the left of Fig. 1) mounted on rock shaft 117.

An arm 118 (Fig. 2) is rigidly secured to 60 rock shaft 117 and pivotally carries at its free end a pawl 118^a extending normally at substantially right angles thereto and presenting a contacting surface in the path of a hook or nose 119 on a rocker arm 119^a 65 that is pivoted at 119^b to the frame. A

right angular extension 118^b of pawl 118^a bears against a stop 118^c on arm 118 and is tensionally held by spring 118^d. Hence forward movement of arm 118 causes pawl 118^a to meet hook 119 and turn rocker arm 119^a 70 upwardly, whose forward surface is curved, forming a rolling bearing for the opposed curved surface of a rocking plate 120 which is fast on shaft 121 and has rigid therewith a hammer frame 122, said shaft also loosely 75 carrying the hammers 123, normally supported by said frame in extended position for striking.

There are as many hammers as type bars and they are impelled toward the type bars 80 with increasing velocity in their approach on account of the rolling motion given rocking plate 120 by rocker arm 119^a.

The hammers 123 swing around the shaft 121 and are operated by means of the horizontal portion 122^a of frame 122. When the handle 116 is operated, motion will be communicated through rock shaft 117, arm 118, rocker arm 119^a and rocking plate 120 to the hammer frame 122, said frame thereby 90 carrying all the hammers with it, until the pawl 118^a slips off the hook or nose 119, when the frame 122, rocking plate 120 and hammers will return to normal position by gravity, the rocking arm 119^a also resuming its normal position under the influence of gravity and pressure of rocking plate 120. It will be understood that the rolling motion derived from the opposed curved surfaces of rocker arm 119^a and rocking 100 plate 120, and the angular relation between these members permits a relatively slow movement of handle 116 to be speeded up in transmission to hammer frame 122, through the rolling motion between rocking arm 119^a and rocking plate 120, to impart a 105 degree of momentum to the free hammers, enabling the latter to strike the type bars with force for manifolding.

Shaft 117 has a rearwardly extending arm 118 on which is mounted a pawl 125 pivoted at 125^a and drawn against a stop 125^b by a spring 125^c. The upper end of pawl 125 is directed toward a projection 129^a on a lever 129 forming part of a toggle with lever 130 to which it is pivotally secured at 130^a and at its outer end at 130^b to the arm 126 mounted at 126^a. At the lower end of arm 126 is secured one end of a knife edge lock 131. There is a duplication of arm 126 and toggle arms 129, 130 to support the knife edge lock 131 at each end and transmit parallel motion thereto, and these arms are rigidly mounted on their respective shafts, that is to say toggle arms 129 are rigid with shaft 133 and arms 126 rigid with shaft 126^a.

The spring 134 serves to return the toggle levers 129 and 130 and lock 131 to retain the latter in normal position. The type 130

bars 105 at their lower ends are provided with slots 105^a with flaring openings with which the knife edge 131^a of the lock engages. Normally, the lock 131 is clear of 5 the type bars, but as soon as the main handle is operated and motion imparted to the arm 124, the pawl 125 will actuate the toggle levers 129, 130, and cause the lock to engage whatever flaring slots 105^a in the 10 type bars 105 are opposite. The pawl 125 will operate the toggle levers 129 and 130 until they reach a straight line, and further contact, holding the toggle levers in this 15 position, will depend upon the length of nose of pawl 125 and also its adjustment by the stop 125^b, the object of which is to maintain the lock in engagement with the type bars until after the hammers have caused the type bars to impinge against the 20 platen. As soon as this has occurred, the pawl 125 slips off the projection on lever 129 and permits the toggle levers 129 and 130 and lock 131 to resume their normal 25 position by reason of the spring 134. It will be noted that pawl 125, after having slipped past the projection on lever 129, can in returning to normal position ride over it and resume the position shown. Simultaneously the pawl 118^a on arm 118 will 30 have communicated motion through nose or hook 119 to rocker arm 119^a and rocker plate 120 and caused the hammers 123 to impinge against the type bars 105 and caused the type thereon to strike the 35 platen 108.

So far as explained, when the handle 116 is operated all the type bars will be locked into alining position in whatever slots are opposite to the lock 131 and the hammers 40 will be operated, causing all the type bars to impinge against the platen. To prevent the impression of those type bars to the left of the item set up, in case such item requires less than the full complement of 45 type bars, I provide a shutter 135 mounted on shoulder screw 136 (Figs. 2 and 10) located in the center approximately of the type bars and provided with a horizontal branch 135^b pivotally connected to the link 50 137 at the bottom of which is the slot 137^a (Fig. 10^a) which is provided to receive a shoulder stud 138^a on crank arm 138 rigidly secured to the rock shaft 117. A spring 139 tends to bear the shutter toward the 55 right (to the left in Fig. 1), namely for the turned lip 135^a at the top to pass over all the type bars that have not been raised from their normal position. When the operating 60 handle is at normal, stud 138^a will contact with the upper end of the slot 137^a in link 137 (Fig. 10^a) and return the shutter 135 to the position shown in Fig. 1, but as soon as the handle 116 is operated, the stud 138^a 65 will move down and allow the link to be depressed by the spring 139 as the shutter

rotates around its pivot until arrested by the turned lip 135^a coming in contact with a type bar raised above the normal or zero position. The shutter extends to the left in Fig. 10 of the turned lip 135^a and will 70 serve to arrest any of the hammers 123 from coming in contact with the type bars 105 through being interposed between them. All those hammers to the right in Fig. 10 of the shutter will be free to come 75 in contact with the type bars. Fig. 10 shows the lip 135^a in contact with the third type bar from the left and the shutter 135 is in front of the two left hand type bars in a position to prevent the hammers con- 80 tacting with the latter.

It will be understood that in the operation so far explained, when the handle 116 is operated the type bars will be locked through their slots 105^a being engaged by 85 the lock 131 and simultaneously the hammer frame 122 and hammers 123 will be rocked around their pivot while at the same time the shutter 135 will be interposed between the hammers and type bars to the 90 extent determined by the turned lip 135^a contacting with the first type bar that is raised above normal or zero position and in a continued movement of the handle the 95 hammers will strike the type bars or the shutter 135 according to the location of the shutter determined by the item set up in the type bars. A continued movement of the handle will release the hammers through pawl 118^a slipping past the nose 119 100 which is timed to take place just as the hammers are coming in contact with the shutter while those hammers not arrested by the shutter will impinge against the respective type bars through momentum and 105 immediately thereafter the handle will then release the lock through the pawl 125 slipping past the projecting portion 129^a of toggle lever 129.

The gear teeth which depend from the 110 rack bar 103 with which each key bar is equipped are adapted to engage with laterally projecting pins 140^a arranged in a circle on the right hand sides (left in Fig. 1) of each of a series of number or registering 115 wheels 140 which I term adding wheels. These adding wheels are loosely mounted on a vertically shiftable shaft 141, which is mounted in supports 142 at opposite sides of the machine (Figs. 3 and 4), said supports 120 being provided at their lower ends with longitudinal slots 142^a engaging shoulders of screws 142^b secured at each side of the frame and permitting movement in a perpendicular direction, while at the upper ends the 125 supports 142 are mounted on studs 143 rigidly fastened to arms 146 journaled to the frame at 146^a at each side of frame and connected together by the strap 146^c seen in cross section in Figs. 2 and 3. To the stud 130

143 is mounted the lever 144 pivoted at 145^a to lever 145 which is rigidly secured to transverse rock shaft 145^b. The levers 144 and 145 form a toggle joint for raising and lowering the adding wheels into and out of engagement with the rack bars 103. There is a duplication of the toggle joint at both sides of the machine, the levers 144 and 145 being at the right side while at the left the levers 213 and 212 (Fig. 9) have the same dimensions and will be referred to later.

The toggle joints aforesaid are operated by a reciprocating bar 147, (Figs. 2 and 3) pivotally connected at its rear end with an arm 147^a extending upwardly from rock shaft 117 and having like connection at its forward end with a swinging arm 147^b pivoted at 147^c to the frame. Bar 147 bears the oppositely directed pawls 148, 149, pivoted at their adjacent ends, as at 148^a and 149^a, respectively, and tensionally held normally in substantial parallelism with bar 147 as by spring 147^d which draws them respectively against stops 148^b and 149^b on bar 147. The end faces of pawls 148, 149 are extended downwardly for operating purposes, pawl 148 in the forward movement of bar 147 meeting in its path a pin 145^d on toggle lever 145, thereby moving toggle levers 145, 144 to their full extended position and lifting adding wheels 140 into engagement with rack bar 103, in which extended position pin 144^a on lever 144 will have traveled in the loose curved slot 145^e from the forward to the rear end of said slot thereby providing a stop to limit the movement of the toggle joint at each end. At this point in the movement of bar 147 pawl 148 will slip over pin 145^c and during its further progress pawl 149 will slip over pin 145^c on lever 145 which has entered the path of said pawl. In the return movement of bar 147 (with the backward swing of handle 116 under the tension of spring 116^a Fig 8), pawl 149 will meet pin 145^c and operate the toggle joint to lower shaft 141, removing adding wheels 140 from engagement with rack bars 103. This return toggle action so far as slack therein is concerned, is assisted by a spring 150 pulling upon a lever 150^a fulcrumed at 150^b and connecting by a pivotal link 150^c with lever 144, said link exerting a thrust upon said lever whenever the link is beyond the vertical position and thereby exerting tension in either direction as also a locking action by pressure of either end of slot 145^e against pin 144^a.

During the time that the teeth of rack bars 103 are in co-operative engagement with the adding wheels 140 (which is during that part of the forward movement of bar 147 in which pawl 148 has acted upon pin 145^d to straighten toggle levers 145 and 144, thereby moving the adding wheels toward rack bars 103) the adding wheels 140 are rotated owing to the rack bars 103 being re-

turned (slid rearward or upward) to their original positions by the following mechanism: Pivoted to rock shaft 117 and extending forwardly therefrom is a lever 151 to which is pivoted at 151^a another lever 152 forming a toggle joint (Figs. 2 and 3), the free end of lever 152 being pivoted at 152^a to a rocker arm 153 fulcrumed on shaft 104^a and having forward extensions 153^a carrying a transverse bail or universal bar 153^b which lies normally in advance of the bell levers 104, which I term sub-levers, said bail being adapted to return the sub-levers, with the rack bars 103, key bars 101 and type bars 105 to their original positions, after they have been set through the manual operation of the finger keys. There is a duplication of levers 151, 152 and 153 in order to insure parallelism of movement. The complete forward pull of handle 116 accomplishes the aforesaid result, this action straightening out toggle levers 151 and 152 and causing rocker arm 153 to swing about shaft 104^a with diminishing speed, bail 153^b in the arc of its travel thus provided meeting the sub-levers 104 in their set positions and returning them with their associated members without undue jar or shock because of the diminishing rate of travel consequent to the toggle action. The adding wheels 140 will therefore be rotated by the racks 103 belonging to the key bars 101 which had previously been moved from their original positions. According to the greater or smaller extent to which the key bars 101 and rack bars 103 had been moved, their return movement will be greater or smaller and the adding wheels 140 will be rotated correspondingly. It will be understood, of course, that the number of spaces or divisions of the plates 102 will agree in width with the teeth of rack 103, and that each of the wheels 140 has ten teeth or pins 140^a and bears on its periphery ten consecutive number indications (0 to 9). While the key bars 102 are set at such distances apart as will allow them to be operated conveniently by the user's fingers, the type bars 105 are set together much more closely, corresponding (more or less) to the letter spacing customary in recording machines.

The wheels 140 which are mounted to turn freely upon their shaft 141 are engaged against rotation when in their normal or lower position, after disengagement from the key bar racks, by pins 140^a on each wheel meshing between the upstanding teeth 154^a (Figs. 2 and 4) of vertical carry arms 154, pivoted, one carry arm for each wheel, on a fixed shaft 155. Also mounted on shaft 155 is a frame consisting of upwardly extending arms 155^a in pivotal engagement by links 155^b, with extensions 155^c of rocker arms 153 at each side; the forward arms 155^d of said frame carrying a transverse bail

or universal bar 156. Tension is applied to carry arms 154 by springs 154^b to draw them forwardly in carrying against a stop, as 154^c, and said carry arms are adapted to be set to the tripping position by being rocked rearwardly and momentarily retained while the adding wheels engage them by the bail 156 meeting the forward edges of said carry arms in the arc of its movement as rocked through the medium of links 155^b and arm 155^a forming a toggle in the actuation of rocker arm 153 aforesaid.

The "carrying" mechanism includes the following instrumentalities: Each adding wheel 140 has a single or "tens" pin 156^a, shown on the side of the wheel opposite to that carrying the pins 140^a (Figs. 2 and 4). This "tens" pin extends tangentially from the wheel perimeter over a portion of the wheel radius and thence centrally to its hub, in this manner serving a twofold purpose to be referred to hereinafter. The carry arms 154 each have a pawl 157 pivoted thereto at 157^a and extended out to be in the path of a right angular tooth 158^a at one end of a horizontally swinging bar or trip lever 158, pivoted at 158^b to a transverse bar 159 secured to each side of the machine frame, duplicate bars, 158 being provided for each of the adding wheels, except for that one at the extreme left side of the machine, or right side of Fig. 1, which has a modified swinging bar 158^a having hook 158^b tensionally held in the path of the "tens" pin of its adding wheel to serve as a solid lock therefor. The opposite end of each swinging bar 158 has a right angular tooth 158^c (Figs. 1 and 7) in the path of one of a series of lugs 160^a which project rearwardly from a transverse bar 160, pivoted by links 160^b to the frame, one of said links 160^b having a right angular extension 160^c having a projecting stud 160^d. Said stud 160^d is in the rearward path of the offset nose 161^c of a pawl 161 that is pivoted at 161^b to the forward extension 146^b of right hand arm 146, which arm may be termed a rocker arm because it rocks on its fulcrum 146^a in the vertical shifting movement of supports 142.

The pawl 161 is drawn over an eccentrically mounted stop 161^a by a spring 161^d to be incapable of forward motion, and said cam may be adjusted to vary the angularity of said pawl in its set position. With a downward rock motion of extension 146^b, caused by the upward shift motion of supports 142, the offset nose 161^c presses against stud 160^d and through said stud and bell lever 160^b, 160^c, swings bar 160 to the right in Fig. 1 causing the teeth 160^a on said bar to rock the swinging bars 158, (or such of them as have been displaced) back to their positions in line with the pawls 157, in readiness for holding the carry arms 154. Said offset nose 161^c by reason of its upper cam surface passes under stud 160^d near the limit of its movement, thereby releasing said stud and allowing bar 160 to be returned by spring 160^e and its teeth 160^a to normal position shown in Fig. 1 out of contact with teeth 158^c. The bars 158 each have superposed thereon a parallel bar 163, slidably engaged therewith by straps 163^a (Fig. 7^A) and each bar having at its rear end (to the left in Fig. 6) a lateral projection 163^b adapted to lie normally in the path of a "tens pin" 156^a, to be shifted longitudinally by said "tens pin" in the rotation of its adding wheel, and thereby to release said bar 163, at its other end, from engagement which it had by a stepped recess 163^c with a lug 164^a on a rigid transverse bar 164. As thus released the bar 163, with its associated bar 158, is swung on pivot 158^b under the tension of spring 165 which extends rearwardly in a diagonal direction from the forward end of bar 163 to bar 159, as shown by dotted lines Fig. 6, the rear ends of bars 163 and 158 under the same influence, being moved away from their associated adding wheel, that is to say, projection 163^b will be out of the path of its "tens pin" 156^a and the tooth 158^a of bar 158 is removed from the path of pawl 157 on carry arm 154 to the left thereof (to the right in Fig. 1), freeing said carry arm and allowing the tension of its spring 154^b to draw it forward to the carrying position, namely against stop 154^c. The bars 163, 158 will be retained in such tripped position by reason of the tension of spring 165 drawing them to the right (left in Fig. 1) and drawing bar 163 to the rear (left in Fig. 6) until the transverse bar 160 is operated, as heretofore explained, and by means of the lugs 160^a caused to reset those bars 163, 158 which have been tripped, by bearing them to the left (right in Fig. 1) until lug 164^a is opposite to recess 163^c and by reason of the tension of spring 165 to engage said recess and thereby retain the bars in their normal position. The tripping action of bars 163, 158 by the tens pins 156^a may take place in either position of the adding wheels since the tens pins are longer than the shifting movement of the adding wheels by the toggles 144, 145.

Assuming an item to have been set up by the manual operation of the key bars 101, 120 and handle 116 is then operated, the lock 131, shutter 135 and hammers 123 will be operated as explained; and the adding wheels will be shifted upwardly by the pawl 148 acting on pin 145^d thereby extending the 125 toggles and bringing the adding wheels into mesh with racks 103 and out of engagement with carry arms 154. At the same time the bars 163, 158 that have been tripped in a previous operation will be reset by the teeth 130

160^a on the transverse bar 160 through bell lever 160^b, 160^c, being actuated by the pawl 161 on arm 146^b. Continued movement of operating handle 116 will cause the bail 153^b 5 through toggle action of levers 151, 152 to meet the sub-levers 104 in its rearward motion and return them to normal position and the key bars 101 to zero, at the same time turning wheels 140 the number of teeth designated by the item set up. During such rotation of the adding wheels if any wheel is moved beyond nine then between the movement of that wheel between 9 and 0 the tens pin 156^a will actuate the corresponding tooth 10 163^b of bar 163 and cause it and bar 158 to be tripped by the action of spring 165, simultaneously the rear tooth 158^a will release its corresponding carry arm 154 through moving out of the path of the pawl 157 and 15 the spring 154^b will then impel the carry arm to the stop 154^c as shown in dotted lines in Fig. 2. Such movement of the carry arm 154 will not be effective because the adding wheels being disengaged therefrom and 20 meshing with racks 103 no result will ensue until later.

The bail 156 which receives a rearward impulse through the links 155^b meets the forward edges of those carry arms 154 which 25 have been tripped into the carrying position, and moves said advanced carry arms rearwardly against the tension of their springs 154^b to a rearward position where their pawls 157 will lie behind the tripping levers 158, said bail tarrying under its toggle actuated action aforesaid in said rearward position. The operating handle will now be at the end of its movement and when released it returns by tension of spring 116^a 30 and the pawl 149 on bar 147 comes in contact with pin 145^c causing a breaking action of toggle levers 144, 145 and the unmeshing of the adding wheels with racks 103 and engagement of the adding wheels with the 35 carry arms 154 which in the meantime have been held practically inert by the bail 156. Upon the further return of the operating handle 116 the bail 156 will move away from the carry arms 154 and any carry arms that 40 are not retained by rear teeth 158^a of bars 158 by contact with the respective pawls 157 will by reason of the tripping action of bars 163, 158, be caused to carry their corresponding adding wheels one tooth as will now 45 readily be understood. If any wheel so carried happens to move from 9 to 0 its tens tooth 156^a will cause a tripping action of bars 163, 158 thereby releasing the carry arm in engagement with the adding wheel of the 50 next higher order to the left (to the right in Fig. 1) to be carried one tooth by the same process.

The bars 163, 158 that have been tripped will remain in such position until the toggle levers are again operated to cause them to

be reset and the carry arms will likewise remain in their abnormal position (those that have been released) until the operating handle is operated and bail 156 returns them to normal position.

70

The reading line of numerals upon the wheels 140 is visible to the operator through observation openings 115^b in the frame plate 115 of the machine.

• At each return stroke of the handle 116, 75 the platen 108 is turned so as to obtain the proper line spacing. For this purpose a curved link 170 is connected by a slot 170^c to the tail of arm 118, by pin 170^a (Fig. 2) and extends upwardly against one of the 80 C-shaped side frames 109 to one arm of a bell-lever 171 pivoted at 171^a to said frame, a second curved link 170^b extending from the other arm of said bell-lever to a rocker arm 173 mounted on the platen shaft 108^a, 85 said rocker arm carrying a pivotal dog 173^a adapted to engage with a ratchet wheel 174 that is fast on shaft 108^a to rotate said shaft and the platen the space of one or more ratchet teeth with every return stroke of 90 handle 116, a spring 171^b causing said dog 173^a to ride over one or more teeth upon the forward stroke of the handle. A detent 174^a is pivoted at 174^b and held by a spring 174^c against the teeth of ratchet wheel 174 to retain it in position.

95

A particular advantage accruing to the use of the connector composed of the links 170, 170^b and bell lever 171 with which to rotate the platen in line spacing is that by 100 this means, the connector, being carried out beyond the clearance 113 designed for the admission of wide sheets of paper, is in non-interfering relation therewith.

The following device is provided for feeding the ink ribbon and for reversing it periodically: A frame 180 (Fig. 1) extending transversely of the machine, in advance of the platen, is centrally pivoted to the machine frame, as by pivot 180^a, on which it 110 is adapted to rock horizontally. Said frame rotatably carries a parallel shaft 181, having the oppositely cut worm threads 181^a, 181^b near its respective ends, which threads are adapted to alternately enter into meshed 115 engagement with respectively adjacent gears 182, 183 which themselves are respectively associated with ribbon spools 182^a, 183^a, having ink ribbon carried thereby and extending between said spools across the line of 120 work. A ratchet wheel 184 mounted at one end of shaft 181 is adapted to be turned (step by step) or a number of teeth at one stroke, by a pawl 184^a pivoted to an arm 185, secured by a shoulder rivet 185^a to a 125 vertical link 185^b that is pivoted at its lower end to the extremity of an arm 186 extending forwardly from rock shaft 117 (Fig. 3). It will therefore be seen that each forward movement of handle 116, through the 130

means described, will cause the ratchet wheel 184, carrying shaft 181 to be rotated one step or a number of ratchet teeth. The means by which this feed movement is alternately communicated to the two ribbon spools is as follows:

Parallel arms 185^c for each spool are journaled on the spool shaft 185^d and extend rearwardly from said shaft at an outward angle, said arms beyond the spool having an upright stud 185^e over which the ribbon 186^a passes in its passage to the spool shown in dotted lines in Fig. 1. Integral with the arms 185^c for each spool, is an inwardly inclined arm 187, terminating in an outwardly extending conical or projectile nose shaped projection 187^b adjacent to the face of a cam disk 188 on shaft 181. The extended portions of arms 187 are connected with a spring 188^a, serving to hold said arms normally drawn inwardly against stops 188^b, and holding the arms 185^c outwardly extended. The feed movement is communicated by one of the worm threads to the gear on its adjacent spool until the other spool has been emptied, at which time the inwardly directed tension of the taut ribbon against upright stud 185^e of arms 185^c belonging to the emptied spool, as the spool 183^a in Fig. 1, draws the associated arm 187 outwardly, whereupon the conical, or projectile nose shaped projection 187^b on arm 187, having the peripheral edge of the disk 188 connected with worm thread 181^a in its path, slides over said cam disk, and on account of the conformation aforesaid of said projection 187^b, rocks the shaft 181 to disengage worm thread 181^b from gear 182 and simultaneously engages worm thread 181^a with gear 183, thereby reversing the direction of travel of the ribbon. This movement is reversed when spool 182^a becomes emptied. A detail of the lock for retaining the meshed engagement between a worm thread and its gear until disengaged by the positive means just described is shown in Fig. 1^a, wherein the frame 180 is seen to carry a pin 189^a having a link 189^b, pivoted at 189^c to lever 189^d fulcrumed at 189^e, a spring 189^f exerting tension on said lever, link, and frame to hold said frame tensionally locked in either position to which it may be rocked. A pivotal detent 190 is spring held against each gear 182, 183 to prevent free or accidental rotation of the ribbon spools. The platen 108 may be turned by hand when desired, by means of a milled knob 108^b.

In order to compel the user to give the handle 116 a complete forward throw, until it engages a stop 200, I provide the following mechanism which prevents the return movement of the handle until it has been brought fully forward: Referring to Fig. 8, on the rock shaft 117 is secured a toothed

sector 201 adapted to engage a pawl 202 fulcrumed to a shaft 202^a which also carries a movable member to be described hereinafter, and pulled (when free) by a spring 203 in such a direction as to stand normally 70 radially with respect to the sector. That is to say, the center of the shaft 117, the fulcrum 202^a, and the fixed end of the spring 203 are in a straight line. Normally the sector 201 is not in engagement with the 75 pawl 202. When the shaft 117 is swung forward from its rear stop 201^a the sector 201 comes in engagement with the pawl 202 and swings it on its fulcrum (contra clockwise in Fig. 8) so that the pawl no longer 80 stands radially, but will prevent a return of the sector 201 and shaft 117. The pawl will of course allow the forward motion of the sector to continue. At the end of this forward motion, the pawl 202 will slip off 85 the rear edge of the sector 201, and the spring 203 will at once restore the pawl to its radial position. The return movement of the shaft 117 is no longer prevented. During such return movement, the sector 90 201 will again come in engagement with the pawl 202, swinging the latter on its pivot in the opposite direction (clockwise in Fig. 8), so that the return movement of the shaft 117 must be completed before said shaft can 95 be moved forward again.

From the above description it will be clear how the items are "set up" and printed on paper, also how the total is registered by means of the adding wheels 140. I still 100 have to describe the mechanism for printing the totals and for setting the adding wheels 140 back to zero. At the left hand side of the machine (to the right of Fig. 1) is located the zero handle 204 carried by a rock 105 shaft 205 provided with a sector 206 (Fig. 9) having stops 206^a, 206^b respectively to limit its rearward and forward movements which in the arc of its travel forwardly meets and is held against return by a pawl 207, fulcrumed at 208 and held by spring 209 with respect to sector 206 in the same manner as the pawl 202 is held with relation to sector 201, said pawl 207 preventing the return of sector 206 until it has passed beyond the influence of said pawl, and said pawl 207 operating similarly as a bar against retraction of said sector 206 in the return path of the latter. One function of the zero handle 204 being to cause the return 110 of the adding wheels to their zero positions (namely to their rotated positions where the zero characters on said wheels are exposed through the observation openings 115^b), I provide an arm 208^a extending upwardly from rock shaft 205 (Fig. 8), said arm having a pin and slot connection with a link 209, pivoted at 210^a to a spur 210^b on a toothed segment or quadrant 210, fulcrumed at 210^c to one of the supports 142 for wheel 115 120 125 130

shaft 141, the teeth 210^a of said segment being in mesh with a pinion 211 fast on shaft 141. The slot 208^b in link 209 having pin 209^a on arm 208^a, allows the same degree of 5 vertical play or lost motion between these members as exists between stud 142^b and slot 142^a in the range of reciprocating movement of support 142. The teeth of segment 210 and pinion 211 are continually in mesh, and any 10 slack or lost motion in said segment, after its return to normal position, is taken up by a spring 211^a attached to spur 210^b and exerting upward tension thereon. It will therefore be seen that the forward movement 15 of zero handle 204 through the instrumentalities described, the segment 210 having as many teeth as pinion 211, accomplishes a complete reverse revolution of shaft 141. In order to note the effect had by this 20 movement of shaft 141 on the adding wheels, it must be remembered that the wheels 140 are normally free to rotate on shaft 141, excepting in their lower position where they are ~~meshed~~ with the carry arms 154, by 25 which they are held against rotation. The wheel return or zero setting mechanism is however operable when the wheels 140 have been raised by the toggle mechanism previously described as controlled by the forward movement of handle 116, which toggle mechanism is also controlled by the zero handle 204 in the following manner.

Mounted on rock shaft 145^b (Fig. 9) is a lever 212, pivoted at 212^a to a lever 213 and 35 forming therewith a toggle joint disposed at that side of the machine opposite to the toggle levers 144, 145, said lever 213 also being pivoted on a stud in line with stud 143, whereby the toggle joints at both sides 40 of the machine may operate in unison.

In order to operate the toggle joint included in the zero handle train of mechanism, I provide an arcuate lever 214, fulcrumed to the frame at 214^c at the rear of 45 shaft 145^b and at the upper forward end of said lever it is connected by a pivoted link 214^a, by pivotal engagement at 212^b, with lever 212, near the upper end thereof, in such arrangement that a forward thrust of 50 link 214^a (to the right in Fig. 9) impelled by lever 214, upon lever 212, will straighten the toggle joint of levers 212, 213, thereby accomplishing the same elevating act for shaft 141 as that described in the operation 55 of the toggle levers 144, 145. The impulse referred to as imparted by arcuate lever 214 is derived from the sector 206, through a pawl 215 pivoted on the side thereof at 215^a, and held with its forward end substantially in the direction of travel of said sector by a spring 215^b drawing the rear end of said pawl against a stop 215^c. As thus supported, the path of said pawl 215 includes a stop pin 214^b on lever 214 and the 60 forward movement of sector 206, through

pawl 215 and pin 214^b is therefore communicated to lever 214, link 214^a and toggle lever 212, for the purpose set forth. When the sector 206 has moved so far forward that the toggle joint acted upon has become straightened out or extended in full, the directional positions of pawl 215 and pin 214^b will have altered to the extent that pawl 215 will slip under pin 214^b and therefore cease to exert pressure thereon. 75

In the further advance of sector 206, (the rock shaft 205 Fig. 8 requiring to continue its motion in order to actuate the gear sector 210, the lost motion in the pin and slot connections therewith having been absorbed 80 during that part of the rock shaft motion effective in straightening the toggle joint), a rearwardly directed pawl 216, pivoted at 216^a to said sector, and normally drawn at its rear end against a stop pin 216^b by a spring 216^c, slips over the stop pin 214^b, and thus has said stop pin in its path on the return movement of sector 206. Thus the setting of the totals on the type bars into printing position is accomplished by the forward movement of zero handle 204, which movement first raises the adding wheels, with their accumulated enumerations, into mesh with racks 103, and then through gear sector 210 and pinion 211, (with the aid of 85 means to be described) turns said wheels back to zero, in that act said wheels carrying with them the racks 103, and, consequently, causing the sub-levers 104 to move the type bars 105 to bring types bearing the 90 numerals representing the total into printing position. 95

The assisting means in the zero setting operation stated as requiring description 100 comprises a sliding feather or spline 217 located in a groove 217^a in shaft 141, said spline carrying teeth 217^b which are normally out of the rotary path of the "tens" pins 156^a on the adding wheels, said teeth 217^b being held in their normal disengaging 105 positions by means of a spring 217^c, placed in a hollowed out end portion of said shaft, and exerting pressure against a plunger 217^d which lies between said spring and spline 217 and presses the latter from right 110 to left, in Fig. 4, the opposite end of said spline bearing against a plunger 217^e which under the normal condition recited extends at the left (Fig. 4) beyond the shaft. The end of said plunger 217^e is adapted to be 115 met by a rocking dog 218, pivoted at 218^a, by the cam surface 219 of a segment 219^a (Fig. 9), pivoted at 219^b, riding up under a right angularly extending arm 218^b of dog 218, rocking said dog inwardly and causing it 120 to retract plunger 217^e with spline 217 against spring 217^c, in this act bringing the teeth 217^b of said spline into the path of the inner or radial portion of the "tens" pins 156^a, whereby in the rotation of the shaft 125 130

141 aforesaid its spline teeth meet the "tens" pins of the adding wheels and turn the latter back to zero.

The cam segment 219^a referred to as the 5 operating member for dog 218, is fulcrumed at 219^b, has an extending arm 221 pivoted at 221^a to a link 221^b which is pivoted at 221^c on sector 206, which sector, as a rigid part 10 of rock shaft 205, is the prime mover in the shifting action of the shaft 141 just referred to. Also in the forward throw of handle 204, a link 222, extending upwardly from a pivotal connection at 222^a with a rearwardly extending arm 222^b from rock shaft 205, and having pivotal connection at 222^c 15 with a sector 223, fulcrumed at 202^a, swings said sector 223 rearwardly in the performance of the following functions: Said sector 223, upon which the pawl 202 is spring held 20 by spring 203 in its normal position holds said pawl operatively with respect to its engagement with sector 201, but when swung rearwardly by link 222, thereby moves pawl 202 out of the path of the teeth of sector 25 201, and instead, the arcuate edge 223^a of said sector 223 passes under a stop pin 224 mounted on the side of sector 201. During this passage, which occurs while the adding wheels are being elevated into engagement 30 with racks 103, the edge 223^a of sector 223 being engaged by stop pin 224, effectually prevents forward movement of sector 201, rock shaft 117 and handle 116, and therefore the operator is prevented from 35 performing any printing operation in this transition stage. But as soon as the sector 223 has been swung far enough for its opposite end to clear the stop pin 224, it will then provide a clearance in the stepped recess 225 to permit the sector 201 to be brought 40 forwardly, a shoulder 225^a on said sector in said recess forming a limit for engagement by said stop pin 224 in the partial movement of said sector 201 which is thus permitted. Said partial movement is sufficient 45 to allow the handle 116 to rock the rock shaft 117 in the performance of the printing operation, but is not sufficient to permit the bail 153^b to act upon the sub-levers 104. 50 I have stated heretofore that the movement forward of the zero handle is arrested by stop 206^b, but the adding wheels are prevented from throwing beyond the zero position through the tens pins 156^a abutting 55 against the projections 163^b of trip bars 163 on the opposite side from that which is effective when carrying takes place because of the reverse direction of the adding wheels when rotated by the zero handle. In Fig. 60 2 upon the operation of the zero handle the shaft 141 and wheels 140 are rotated clockwise or reversely to the adding rotation imparted by handle 116 when carrying is accomplished. It will be observed in Fig. 65 that when a tens pin abuts on the right side

of projection 163^b, the trip bar 163 is merely forced at its other end against lug 164^a without effect, while in the adding and carrying operation the tens pin contacts on its left side with projection 163^b in Fig. 6. 70

By reason of the tangential arrangement of each tens pin 156^a from a given point in the radius of its wheels 140 out to the periphery thereof, the extent of this tangential arrangement covering the range of vertical movement of the wheels, the wheels are retained at the zero position more accurately than would be the case if the tens pins were radially disposed at the time when the wheels return into engagement with the 75 carry arms 154. The disposition is such that the direction of shifting movement of the wheels and the position of the tens pins at this time are parallel. The adding wheel to the right in Fig. 1 is arrested at the zero position by the pawl 158^a which permits the tens pin to ride past while rotating in the other direction in the act of adding. Therefore, with the zero handle advanced, the adding wheels raised into engagement with 80 racks 103, the wheels turned and their enumerations or totals imparted to the type numerals at the printing zone, the handle 116 can now be pulled partially in order to print said total, the zero handle being held forwardly while the printing is performed. After the printing, first the handle 116 is released and returned by its spring 116^a and then the zero handle 204 is released and returned by its spring 226, which connects a 85 depending arm 226^a on rock shaft 205 with an advanced portion of the frame (Fig. 8). In this return action of zero handle 204 the pawl 216 meets stop pin 214^b and exerting pressure thereon "breaks" the toggle joint 90 of levers 212, 213, thereby lowering wheels 140 into their meshed engagement with the carrying arms 154. 95

In the forward movement of zero arm 204 which has been described as setting the total 100 on the type bars to printing position, the ribbon 186^a which passes through slot 229^b of arm 229 (Fig. 9), has been vibrated vertically, whereby, said ribbon being of bichrome character, namely, as having ink of 105 one color, as purple, at its upper portion, and ink of another color, as red, at its lower portion, it may provide a different color for the printing of the total than for the listing numerals. In performing this function 110 I employ a pivotal link 227, extending horizontally from a spur 227^a on rock shaft 205 to the end of one arm of a bell lever 228, fulcrumed at 228^a and pivotally connecting 115 at the end of its other arm with a vertically extending link 228^b, which is pivoted at its upper end to one of a pair of horizontal rock arms 229 fast to the rock shaft 229^a, to vibrate said rock arms vertically and thus to move the ribbon which is carried in vertical 120 125 130 135

slots 229^b in the rearward ends of said rock arms from the lower to the upper position. After the total has been printed as described, and the zero handle allowed to 5 turn to its original position, two different operations are now possible. If the adding operation has been completed, that is to say, if the printed total is the final result, the key bars 101 which have been lowered by the 10 zero-setting mechanism, are pushed back by hand to their original upper or rear position. This restores all the parts of the machine to the initial or zero position. In some cases, however, the total printed is not the 15 final total, but an intermediate result or "subtotal," that is to say, it is desired to continue adding items to such subtotal. In this case, after the zero handle has returned to its normal position, those key bars 101 20 which are in the lower or forward position are not returned by hand, but the handle 116 is given a complete forward movement in order to set up in the wheels the same item as was removed from them in the zero setting 25 operation, in other words, the adding wheels 140 are rotated by means of the rack bars 103, during the return of the key bars 101, so that when the handle 116 comes back to its initial position, the key bars 101 and 30 the type bars 105 will be in their normal positions, but the adding wheels 140, instead of standing at zero, will show the "subtotal" which has just been printed in purple, being a duplication of the total that was 35 printed in red.

It is very important to prevent the zero and total setting mechanism from being operated while one or more of the key bars 101 and the type bars 105 are out of the zero 40 position. In fact, the zero and total setting device should be operated only with all the key bars 101 in their normal or rear position. For this purpose, each of the levers 104 is provided, adjacent to its fulcrum, with 45 a forwardly facing cam or heel 230 (Fig. 2), and whenever a key bar 101 is moved down (forward), the corresponding cam 230 will push downward on a rod 231 extending across the levers 104 and carried by two 50 arms 231^a fulcrumed on the frame at 231^b, said arms being tensionally drawn toward the frame by spring 231^c to normally hold rod 231 in a depressed seat 231^d therefor in 55 cams 230 (see Fig. 2). Hanging from a pivot 232^a (Fig. 5) borne by an extension 232 of a frame portion which carries the shaft 104^a is a pawl 232^b, to which is connected a spring 232^c tending to draw said pawl to a position in the upward path of an 60 arm 233 on the zero shaft 205, where said pawl will serve as a stop to prevent vertical movement of said arm and thus to lock the zero shaft against operation. But the rod 231 is normally held to prevent forward 65 movement of pawl 232^b by spring 231^c, said

rod lying in a slot 232^d in a link 232^e which is pivoted at 232^f to the rear extension of pawl 232^b.

The rod 231 is forced against the upper end of slot 232^d by spring 231^c which is 70 stronger than spring 232^c and thereby normally retains pawl 232^b out of the path of arm 233, but when a cam 230 is operated, the rod 231 will be moved down and the spring 232^c will then become effective to 75 bring pawl 232^b into the path of arm 233, thus acting as a stop for the zero shaft as stated. This construction will also permit of the return of zero handle and arm 233 when the key bars have been left with the 80 total set up because the pawl 232^b will then be pushed out of the way by the arm 233.

Referring to Fig. 3, it will be observed that also the arms 153^a which carry the universal bar or bail 153^b have beneath them 85 cams 234 adapted to ride over and depress rod 231 to lock the zero shaft when said bail is moving in the performance of its function in returning the sub-levers, said cams 234 having forward inclines 234^a which 90 allow them to freely leave their normal position behind said bar and to depress the latter, the main function of said cams 234 being to lock the zero handle when the 95 operating handle starts to move.

To assist in imparting a comprehensive knowledge of the operation of the various parts in my invention, I will briefly describe hereunder, as far as possible in sequence, the several manual and major mechanical performances therein: The machine being at 100 normal the operator sets an item by sliding the finger key bars downwardly until his finger, bearing against a numeral, comes to rest against stop 115^a. In thus setting the 105 keys the sub-levers 104 will have moved the type-bars 105 to bring the corresponding type in printing relation with respect to the platen. The operator then pulls the handle 116 through a full stroke. The first part of 110 that stroke operates the hammers 123 through bail 122 and rockers 120, 119^a by the action of arm 118 that extends from handle shaft 117. At the same time the shutter 135 has been interposed by selective means 115 between the type bars and those hammers which are not to impact with type bars. While operating the hammers the lock 131 is applied to the type bar racks 105^d through 120 toggles 129, 130 through the action of pawl 125. The reciprocating bar 147, also operated by the handle through arm 147^a, has caused its pawl 148 to reach pin 145^d on toggle lever 145, the toggle joint thus attacked, straightening out and raising shaft 141 with the adding wheels away from their 125 normal seat, where the pins 140^a were in engagement with spring pressed carry arms 154, and taking said wheels into mesh with the racks 103 carried by the sliding key bars 130

101. The upper toggle member 144 has connection with rock arm 146, whose forward extension 146^b has a pawl 161 which, in the toggle straightening action aforesaid shifts 5 a toothed bar 160 and causes the teeth of said bar to set such of the trip-bars 158 as had been tripped back into their normal position where they act as stops to hold the carry arms 154 in normal position. After 10 straightening the toggle joint aforesaid, the bar 147 continues its forward movement to the limit of the handle stroke to cause pawl 149 to come in front of pin 145^c on toggle member 145 in readiness for the return 15 movement. Also in that forward movement of handle 116 the toggle joint 151, 152 has expanded, and, when the wheels have entered mesh with racks 103, the bail 153^b, actuated by said toggle joint, with diminishing 20 speed has moved toward the sub-levers 104 in their variously set positions and carried them back to normal position, thereby returning the key bars to zero. With the movement of toggle 151, 152, another toggle 25 composed of members 155^b, 155^a at the same time moves the bail 156 with diminishing speed toward the carry arms, to reset those that have carried. It will be seen that in the first part of this handle movement the 30 hammers, which were swung for printing, were also released for return by the pawl 118^a passing over nose 119 to release the rocker 119^a; and it will also be seen that the return of the finger keys to zero causes the 35 return of the type bars to zero through connection 104^b. It should be noted that the spring 150 exerts tension to pull down lever 150^a when link 150^c is out of line at either side with toggle member 145, thereby assisting 40 the toggle action in both directions in vibrating or shifting the wheels.

The spring actuated return stroke of handle 116 causes pawl 149 to "break" the toggle joint 144, 145, returning the wheels, 45 with the item set thereon, to their seats in the carry arms. The wheels in their rotation in the forward stroke, will through their tens pins 156^a have tripped any trip levers 158 in the path of said tens pins and thus 50 the carry arms 154, which reengage said adding wheels in the first part of the return stroke aforesaid, before bail 156 leaves them, or due to the slow movement of said bail when in that position; having reengaged 55 said wheels, are enabled, if their trip bar stops have been tripped, to move to the carry position and cause their engaged wheels to "carry." The continued return movement of handle 116 has no further function so far 60 as the major elements are concerned, except to restore bails 156 and 153^b to normal position, also to return the shutter to normal. The turning of the platen for feeding the paper and feeding the ribbon longitudinally 65 are also performed.

The zero handle 204, in its complete stroke performs no adding operation, but through toggle joint 212, 213 moves the adding wheels from the carry arms 154 to the racks 103, and through segment 210 and gear 211 70 on shaft 141 turns the wheels backwardly, communicating the total number or sum aligned on the wheels to the finger keys at the setting line, and also to the type bars at the printing line. In this act the wheels 75 140 may have been removed from the carry arms 154 whether they were in normal or carried position, or some in each, and, on the return stroke of the zero handle said wheels will be returned to the carry arms in 80 the same positions of the latter. It will also be noted that the zero handle in its movement through toggle joints 212, 213 thereby shifting the adding wheels also resets the trip bars 158, 153 or those that have 85 previously been tripped through the pawl 161 on arm 146^b imparting movement to transverse bar 160.

It is believed that the means by which the zero handle forward stroke causes the engagement of shaft 141 with the wheels and returns them to zero is quite apparent, as also the interlocking means preventing the handles 116 and 204 from operating together, and the exception that the handle 116 90 95 may move for the printing operation alone when the handle 204 is fully thrown; also that all other actions and interactions are fully described.

I claim as my invention:

1. In an adding and recording machine, the combination of adding wheels mounted on a shaft capable of vibrating between two positions, rack bars to engage the wheels when the shaft is in one position and free 105 from said wheels when in the other position, tens teeth on the wheels of greater length than the vibrating movement of the shaft, and trip levers mounted on stationary supports, said trip levers lying continually in 110 the paths of said tens teeth to be operable thereby in both positions of the shaft.

2. In an adding and recording machine, the combination of adding wheels mounted on a shaft capable of vibrating between two 115 positions, rack bars to engage the wheels when the shaft is in one position and free from said wheels when in the other position, tens teeth on the wheels of greater length than the vibrating movement of the shaft, 120 and trip levers mounted on stationary supports, said trip levers lying continually in the paths of said tens teeth, and of such construction that the operative relation between the tens teeth and trip levers remains 125 the same in both positions of the adding wheels.

3. In an adding and recording machine, in combination, a series of adding wheels, a shaft therefor, bearings for said shaft at 130

each end thereof, a rock shaft, toggle joints connected each by one arm therewith, the other arms of said toggle joints respectively having supporting connection with said 5 bearings, an operating handle, a reciprocating bar actuated thereby, and means upon said bar to passingly engage and actuate one of said toggle joints in each direction of movement of said bar, to respectively extend 10 and contract said toggle joints and thereby shift said adding wheels between two positions.

4. In an adding and recording machine, in combination, a series of adding wheels, a 15 shaft therefor, bearings for said shaft at each end thereof, a rock shaft, toggle joints connected each by one arm therewith, the other arms of said toggle joints respectively having supporting connection with said 20 bearings, an operating handle, a reciprocating bar actuated thereby, and means upon said bar to passingly engage and actuate one of said toggle joints during a portion only of the movement of said bar in each direction, to respectively extend and contract said 25 toggle joints and thereby shift said adding wheels between two positions.

5. In an adding and recording machine, in combination, a series of adding wheels, a 30 shaft therefor, bearings for said shaft at each end thereof, a rock shaft, toggle joints connected each by one arm therewith, the other arms of said toggle joints respectively having supporting connection with said 35 bearings, springs to yieldingly hold said toggle joints either extended or contracted, an operating handle, a reciprocating bar actuated thereby, and means upon said bar to passingly engage and actuate one of said 40 toggle joints in each direction of movement of said bar, to respectively extend and contract said toggle joints and thereby shift said adding wheels between two positions.

6. In an adding and recording machine, in 45 combination, a series of adding wheels, a shaft therefor, bearings for said shaft at each end thereof, a rock shaft, toggle joints connected each by one arm therewith, the other arms of said toggle joints respectively 50 having supporting connections with said bearings, springs to yieldingly hold said toggle joints either extended or contracted, an operating handle, a reciprocating bar actuated thereby, and means upon said bar to 55 passingly engage and actuate one of said toggle joints during a portion only of the movement of said bar in each direction, to respectively extend and contract said toggle joints and thereby shift said adding wheels between two positions.

7. In an adding and recording machine, in 65 combination, a series of adding wheels, a shaft therefor, bearings for said shaft at each end thereof, a rock shaft, toggle joints connected each by one arm therewith, the

other arms of said toggle joints respectively having supporting connection with said 70 bearings, pins projecting from a toggle arm, an operating handle, a reciprocating bar actuated thereby, pawls upon said bar to passingly engage said pins and actuate said toggle joints in each direction of movement of said bar, to respectively extend and contract said 75 toggle joints and thereby shift said adding wheels between two positions.

8. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said 80 bearings, pins projecting from a toggle arm, an operating handle, a reciprocating bar actuated thereby, pawls upon said bar to passingly engage said pins and actuate said toggle joints during a portion only of the movement of said bar in each direction, to respectively extend and contract said 85 toggle joints and thereby shift said adding wheels 90 between two positions.

9. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said 95 bearings, springs to yieldingly hold said toggle joints either extended or contracted, pins 100 projecting from a toggle arm, an operating handle, a reciprocating bar actuated thereby, pawls upon said bar to passingly engage said pins and actuate said toggle joints in each direction of movement of said bar, to respectively extend and contract said 105 toggle joints and thereby shift said adding wheels between two positions.

10. In an adding and recording machine, in combination, a series of adding wheels, a 110 shaft therefor, bearings for said shaft at each end thereof, a rock shaft, toggle joints connected each by one arm therewith, the other arms of said toggle joints respectively having supporting connection with said 115 bearings, springs to yieldingly hold said toggle joints either extended or contracted, pins projecting from a toggle arm, an operating handle, a reciprocating bar actuated thereby, pawls upon said bar to passingly engage said pins and actuate said 120 toggle joints during a portion only of the movement of said bar in each direction, to respectively extend and contract said toggle joints and thereby shift said adding 125 wheels between two positions.

11. In an adding and recording machine, in combination, a series of adding wheels, a shaft therefor, bearings for said shaft at each end thereof, a rock shaft, toggle joints 130

- connected each by one arm therewith, the other arms of said toggle joints respectively having supporting connection with said bearings, springs to resist the initial extension and assist the final extension of said toggle joints, an operating handle, and means between said toggle joints and handle to passingly operate the former by the latter.

12. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said bearings, springs to resist the initial contraction and assist the final contraction of said toggle joints, an operating handle, and means between said toggle joints and handle to passingly operate the former by the latter.

13. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said bearings, springs to resist the initial and assist the latter part of the movement of said toggle joints in both extending and contracting.

14. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said bearings, springs to resist the initial and assist the latter part of the movement of said toggle joints in both directions, pins projecting from a toggle arm, an operating handle, a reciprocating bar actuated thereby, pawls upon said bar to passingly engage said pins and actuate said toggle joints in each direction of movement of said bar, to respectively extend and contract said toggle joints and thereby shift said adding wheels between two positions.

15. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said bearings, springs to resist the initial and assist the latter part of the movement of said toggle joints in both directions, pins projecting from a toggle arm, an operating handle, a reciprocating bar actuated thereby, pawls upon said bar to passingly engage said pins and actuate said toggle joints in each direction of movement of said bar, to respectively extend and contract said toggle joints and thereby shift said adding wheels between two positions.

16. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said bearings, means for limiting the movements of said toggle joints in both directions, an operating handle, a reciprocating bar actuated thereby, and means upon said bar to passingly engage and actuate one of said toggle joints in each direction of movement of said bar; to respectively extend and contract said toggle joints and thereby shift said adding wheels between two positions.

17. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said bearings, means for guiding the movements of said toggle joints and bearings, an operating handle, a reciprocating bar actuated thereby, and means upon said bar to passingly engage and actuate one of said toggle joints in each direction of movement of said bar, to respectively extend and contract said toggle joints and thereby shift said adding wheels between two positions.

18. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said bearings, a pin and arcuate slot connection between the arms of one of said toggle joints to limit the movement thereof in both directions, an operating handle, a reciprocating bar actuated thereby, and means upon said bar to passingly engage and actuate one of said toggle joints in each direction of movement of said bar, to respectively extend and contract said toggle joints and thereby shift said adding wheels between two positions.

19. In an adding and recording machine, in combination, a series of adding wheels, a shaft therefor, bearings for said shaft at each end thereof, a rock shaft, toggle joints connected each by one arm therewith, the other arms of said toggle joints respectively having supporting connection with said bearings, pins projecting from a toggle arm, an operating handle, a reciprocating bar actuated thereby, pawls upon said bar to passingly engage said pins and actuate said toggle joints in each direction of movement of said bar, to respectively extend and contract said toggle joints and thereby shift said adding wheels between two positions.

said toggle joints in each direction of movement of said bar, to respectively extend and contract said toggle joints and thereby shift said adding wheels between two positions, 5 the relation between the pins and pawls being such that a pin moves out of the path of a pawl after correct motion has been transmitted.

20. In an adding and recording machine, 10 in combination, a series of adding wheels, a shaft therefor, bearings for said shaft at each end thereof, a rock shaft, toggle joints connected each by one arm therewith, the other arms of said toggle joints respectively 15 having supporting connection with said bearings, pins projecting from a toggle arm, an operating handle, a horizontally reciprocating bar actuated thereby, and pawls upon said bar to passingly communicate 20 movement from said bar to said toggle arm, the arcuate motion given a pin by said toggle arm causing it to move below the path of its operating pawl when the toggle joint has been acted upon thereby.

25. 21. In an adding and recording machine, the combination of carry arms, adding wheels, movable supports for said adding wheels to engage them with and disengage them from said carry arms, and a bail for 30 the carry arms so connected to the operating shaft for progressive movement that the carry arms are set thereby to one position and momentarily held therein during the re-engagement of the adding wheels therewith.

35. 22. In an adding and recording machine, the combination of carry arms provided with gear teeth, adding wheels mounted on movable supports to engage with and disengage from the carry arms, and a bail for the 40 carry arms so connected to the operating shaft for progressive movement that the carry arms are set to one position by said bail and momentarily held in practically that position while the adding wheels be- 45 come reengaged therewith.

23. In an adding and recording machine, the combination of spring pressed carry arms and trip levers therefor, adding wheels, movable supports for said adding wheels to 50 move them into and out of engagement with said carry arms, and a bail for the carry arms so connected to the operating shaft for progressive movement that the carry arms are set thereby to one position, said 55 bail detaining the carry arms in that position until the adding wheels are reengaged.

24. In an adding and recording machine, the combination with carry arms having gear teeth, of adding wheels mounted on 60 movable supports and adapted to engage with and disengage from said carry arms, springs impelling the carry arms in the carrying direction, an operating handle connected to said movable supports to cause 65 engagement and disengagement of said add-

ing wheels with relation to said carry arms, and a bail for said carry arms so connected to said handle for progressive movement that the carry arms are set to one position thereby and retained by said bail during the reengagement of the adding wheels.

25. In an adding and recording machine, the combination with carry arms having gear teeth, of adding wheels having movable supports to engage with and disengage 75 from said carry arms, springs impelling the carry arms in the carrying direction, and a bail for the carry arms so connected to the operating shaft for progressive movement that the arms are set to one position thereby 80 and retained by said bail during the reengagement of the adding wheels therewith.

26. In an adding and recording machine, the combination of adding wheels shiftable 85 to two positions, carry arms provided with gear teeth for engagement of adding wheels in one position, a main handle so connected to the adding wheel supports that in its forward motion said wheels are disengaged from the carry arms and engaged in its return movement, a bail for the carry arms progressively operated by the main handle to set the carry arms to one position in the forward movement of the handle and to momentarily retain them in that position during the return of the handle until the adding wheels become reengaged with the carry arms.

27. In an adding and recording machine, the combination of adding wheels shiftable 100 to two positions, carry arms provided with gear teeth for engagement with adding wheels in one position, springs impelling the carry arms to the carry position, trip devices to hold said carry arms and operable by adding wheels in both positions, and a bail to restore those carry arms released by the trip devices while the adding wheels are disengaged from said carry arms to thereby permit a second operation of the 110 latter for the effective carrying of the adding wheels.

28. In an adding and recording machine, the combination of adding wheels, racks for 115 rotating said wheels, sub-levers connected to the racks, a universal bar for engaging the sub-levers, an operating shaft, a toggle joint to transmit motion from said operating shaft to said universal bar, a second universal bar connected to the first by toggle joint, and carry arms acted upon by the second universal bar.

29. In an adding and recording machine, the combination of adding wheels, racks for 125 rotating said wheels, sub-levers connected to the racks, a universal bar for engaging the sub-levers, an operating shaft, a toggle joint to communicate motion from said shaft to said sub-levers, carry arms, tensional means to move said carry arms to the carry posi- 130

- tion, a second universal bar to return said carry arms, and a second toggle joint deriving motion from said first named toggle joint to actuate said second named universal 5 bar.
30. In an adding and recording machine, the combination of carrying mechanism including carry arms movable between two positions, a universal bar to actuate said carry arms in one direction, a toggle joint to operate said universal bar, an operating shaft, and another toggle joint deriving motion from said operating shaft to transmit movement to said first named toggle joint.
- 10 31. In an adding and recording machine, the combination of carrying mechanism including carry arms movable between two positions, a universal bar to actuate said carry arms in one direction, an operating shaft, and a series of toggle joints to variably transmit progressive movement from said shaft to said bar.
- 15 32. In an adding and recording machine, the combination with sub-levers between the finger keys and type bars, adding wheels movable between two positions, carry arms and separate universal bars for said sub-levers and carry arms, of an operating shaft and toggle joints variably transmitting progressive motion from said shaft to said bars and wheels.
- 20 33. An adding and recording machine having adding wheels movable between two positions, sub-levers, and carry arms, together with an operating shaft and variable speed power transmitting mechanism including three distinctly acting toggle joints.
- 25 34. An adding and recording machine wherein the adding wheels are vibrated, and the carry arms, sub-levers, and lock for the type bars are all controlled through mechanism including distinctly operating toggle joints having progressive movement at variable speeds.
- 30 35. In an adding and recording machine, the combination of adding wheels capable of vibration between two positions, movable racks to engage said wheels in one position and spring pressed carry arms to engage said wheels in the other position, said racks having sub-levers movable therewith, together with separate bails to respectively reset said sub-levers and carry arms, a toggle connection for each bail, and means actuating said toggles to operate said bails progressively in synchronism at variable speeds.
- 35 36. In an adding and recording machine, the combination of adding wheels, having operating means, said wheels being capable of vibrating into and out of engagement with said operating means, and carry arms to engage said wheels when disengaged from said operating means, said carry arms being capable of movement to an extent representing one numerical degree of said adding
- wheels, and said carry arms serving to detain the adding wheels against further rotation when the latter are disengaged from said operating means.
- 40 37. In an adding and recording machine, the combination of adding wheels capable of vibration between two positions, said wheels having tens pins of length greater than the extent of their movement, spring pressed carry arms to operate said wheels when in one operative position, trip mechanism comprising a lever pivoted near its center and having a sliding arm thereon, and a tensional lock for said trip mechanism in both positions, said tens pins causing said trip mechanism to trip said carry arms an equal extent in either position of said wheels.
- 45 38. In an adding and recording machine, the combination of adding wheels capable of vibration between two positions, actuating means therefor, carry mechanism for said wheels, and a trip for said carry mechanism, together with means for setting said trip, said means controlled by the means for actuating the wheels in their movement away from said carry arms, and independent of the means whereby the wheels are vibrated.
- 50 39. In an adding and recording machine, the combination of adding wheels, means vibrating them between two positions, spring pressed carry mechanism for said wheels, and a trip for said carry mechanism, together with means for setting said trip controlled by the wheel vibrating means in the movement of said wheels away from said carry arms.
- 55 40. In an adding and recording machine, the combination of adding wheels, tens pins on the wheels, trip mechanism caused to be tripped by the tens pins when the wheels are rotated in one direction and acting as stops when the wheels are rotated in the other direction, a main operating handle to rotate the wheels in one direction, a zero handle to rotate them in the other direction, and means operable by each handle to set said trips to normal at the outset of its movement.
- 60 41. In an adding and recording machine, the combination of adding wheels, tens pins on the wheels, carrying mechanism including trip mechanism engaging the tens pins and thus serving as stops for the wheels when the latter are returned to zero, a zero handle, and means operated by the zero handle for resetting to normal any trips that had been previously tripped.
- 65 42. In an adding and recording machine, the combination of adding wheels, means vibrating them between two positions, spring pressed carry arms to receive said wheels in one position, swinging trip levers to hold said carry arms in normal position, means

on said wheels for tripping the levers and said carry arms once in each revolution of said wheels, allowing them to move to the carry position, means resetting carry arms that have been tripped, and means actuated by the vibrating means for resetting the swinging levers in the movement of said wheels away from said carry arms.

43. In an adding and recording machine, 10 the combination of adding wheels, means vibrating them between two positions, spring pressed carry arms to receive said wheels in one position, swinging levers to hold said carry arms in normal position, a setting bar 15 for said levers, means for tripping said carry arms once in each revolution of said wheels, allowing them to move to the carry position, and a rock arm having a pawl actuated by the wheel vibrating means in the 20 movement of said wheels away from the carry arms, to operate said setting bar to reset said swinging levers as carry arm stops.

44. In an adding and recording machine, 25 the combination of adding wheels, means vibrating them between two positions, spring pressed carry arms to receive said wheels in one position, swinging levers to hold said carry arms in normal position, a setting bar 30 for said levers, means for tripping said carry arms once in each revolution of said wheels, allowing them to move to the carry position, a bail to restore "carried" carry arms to normal position, and a rock arm having a pawl actuated by the wheel vibrating means in the movement of said 35 wheels away from the carry arms, to operate said setting bar to reset said swinging levers as carry arm stops.

45. In an adding and recording machine, 40 the combination of adding wheels, spring pressed carry arms therefor, and trip mechanism consisting of a lever pivoted in approximately its center, with a sliding arm thereon, and a spring set at an angle relatively thereto to hold said lever in both its engaged and disengaged positions with respect to a carry arm.

46. In an adding and recording machine, 50 the combination of adding wheels, spring pressed carry arms therefor, and trip mechanism consisting of a lever pivoted in approximately its center, with a sliding arm thereon, and a spring set at an angle relatively thereto to act on both the pivotal and 55 sliding portions of said trip mechanism.

47. In an adding and recording machine, 60 the combination of adding wheels capable of movement between two positions, spring pressed carry arms therefor, and trip mechanism consisting of a lever pivoted in approximately its center, with a sliding arm thereon, a spring set at an angle relatively thereto to act on both the pivotal and sliding portions of said trip mechanism, and

tens pins on said adding wheels, of greater 65 length than the extent of movement of said wheels, to operate said trip mechanism in either position of said adding wheels.

48. In an adding and recording machine, 70 the combination of adding wheels, a shaft therefor capable of movement between two positions, a pinion on said shaft, a toggle joint to move said shaft, a gear sector to rotate said pinion and shaft reversely, a zero handle, and means operated by said handle 75 to actuate the toggle joint and move the shaft.

49. In an adding and recording machine, 80 the combination of adding wheels, a shaft therefor capable of movement between two positions, a pinion on said shaft, a toggle joint to move said shaft, a gear sector to rotate said pinion and shaft reversely, a zero handle, and means between said handle and toggle joint to operate the latter by the 85 former, a ribbon support, and means between said zero handle and ribbon support to shift the latter in the operation of said handle to bring another portion of the ribbon, having a different color, into printing 90 position.

50. In an adding and recording machine, 95 the combination of sliding racks, sliding type bars, connecting sub-levers for said racks and bars, a bail controlling said sub-levers and having a cam, a spring pressed transverse rod adapted to be moved by said cam, a spring pressed locking pawl controlled by said rod, a zero handle having a projection, and a main operating handle releasing said pawl through the actuation of said cam and rod, causing said pawl to enter the path of the projection on said zero handle as a lock therefor.

51. In an adding and recording machine, 100 the combination with a main operating handle and a zero handle, of means controlled by said zero handle locking said main handle until its own stroke is completed, and then allowing only partial movement of said 105 main handle to perform the printing operation.

52. In an adding and recording machine, 110 in combination, a main operating handle, a sector thereon having a stop, a cam pivoted 115 to enter the path of said stop to prevent operation of said handle, a zero handle, and a connection between said zero handle and cam to move the latter by the former, said cam having a recess which is presented to 120 said stop at the end of the zero handle movement, to permit a partial movement of said main handle.

53. In an adding and recording machine, 125 in combination, a main operating handle and a zero handle, a gear sector for each of said handles, a spring directed pawl in advance of the gear sector for said zero handle

to stay said handle from return until it has completed its throw in either direction, and a spring directed pawl normally held by said zero handle in the path of the gear sector on said main handle to stay said main handle from return until it has completed its throw in either direction.

54. In an adding and recording machine, in combination, a main operating handle 10 and a zero handle, a gear sector for each of said handles, a spring directed pawl in advance of each gear sector to stay said handles from return until the throw of each handle has been completed in either direction, the spring directed pawl acting upon the gear sector for the main handle being under the control of the zero handle and adapted to be removed from the path of the main handle sector when the zero handle is 20 operated.

55. In an adding and recording machine, in combination, a main operating handle and a zero handle, a gear sector for the main handle, a spring directed pawl in advance 25 of the gear sector to stay the main handle from return until it has completed its throw in either direction, said spring being under the control of the zero handle to change the direction of the pawl and take it out of the 30 path of the gear sector for said main handle when the zero handle is operated.

56. In an adding and recording machine having a platen, the combination of racks, sliding type bars slideable across the platen, 35 means connecting the movements of said racks and type bars, said type bars having vertical slots, of a shaft engaging said slots, spring pressed rockers pivoted upon said shaft and rollers or shoes on said rockers 40 bearing against said type bars to retain them and the racks frictionally in set position and to tensionally hold the type bars away from the platen.

57. In an adding and recording machine, 45 the combination of adding wheels shiftable to two positions, carry arms provided with gear teeth for engagement of the said adding wheels in one position, springs impelling the carry arms in the carrying direction, a 50 zero handle connected to shift the said wheels out of and into engagement with said carry arms while the latter are in staggered position, a main handle having similar connection, and a bail connected to the main 55 handle only to reset the said carry arms to one position when the reengagement of the adding wheels is caused by the main handle.

58. In an adding and recording machine, 60 the combination of adding wheels, spring pressed carry arms therefor, trip mechanism for each carry arm consisting of a lever pivoted in approximately its center, with a sliding arm thereon, and a spring to hold said lever in both its engaged and dis-

engaged positions with respect to its carry 65 arm.

59. In an adding and recording machine, the combination of adding wheels, spring pressed carry arms therefor, trip mechanism for each carry arm consisting of a lever 70 pivoted in approximately its center, with a sliding arm thereon, and a spring to act on both the pivotal and sliding portions of set trip mechanism.

60. In an adding and recording machine, 75 the combination of a series of adding wheels mounted on a vibrating shaft shiftable between two positions, and a series of rack bars movable to various determined positions, each rack bar of the series co-operating with 80 a wheel of its series, said wheels when shifted to one position engaging said rack to be variously rotated thereby, trip means, and means on said wheels to co-act with said trip means when the shaft is in either position, 85 to permit the wheels to perform the carry operation.

61. In an adding and recording machine, the combination of adding wheels mounted on a shaft movable to two positions, a tens 90 pin on each wheel extending from the hub to the periphery thereof, the portion at the hub being radial, and the outer portion oblique to a radial line, trip mechanism co-acting with the outer end of the tens pin, and zero 95 returning mechanism co-acting with the inner radial portion of said tens pin.

62. In an adding and recording machine, the combination of adding wheels, spring pressed carry arms therefor, trip mechanism 100 for each carry arm consisting of a lever pivoted in approximately its center, with a sliding arm thereon, and tensional means to hold said lever in both its engaged and disengaged positions with respect to its carry 105 arm.

63. In an adding and recording machine, the combination of adding wheels, spring pressed carry arms therefor, trip mechanism for each carry arm consisting of a lever 110 pivoted in approximately its center, with a sliding arm thereon, and tensional means to act on both the pivotal and sliding portions of said trip mechanism.

64. An adding and recording machine 115 having sliding finger keys and an adjustable finger stop to arrest the movement of said keys.

65. An adding and recording machine having a series of straight, parallel sliding 120 finger keys, each bearing a series of numeral designations, and an adjustable finger stop common to said keys to arrest the operator's finger when sliding a key to bring a numeral thereon to set position.

66. An adding and recording machine 125 having a series of sliding type bars and sliding finger keys with intermediate connec-

tions, said type bars and finger keys bearing corresponding series of numeral designations, and an adjustable finger stop common to said keys to arrest the operator's finger when sliding a key to bring a numeral on a type bar to printing position.

67. An adding and recording machine having a series of straight, parallel sliding finger keys separately movable forwardly to 10 set positions, each key having a rear projec-

tion whereby a number of said keys may be swept rearwardly to normal position in a single movement.

In testimony whereof, I have hereunto signed my name in the presence of two sub- 15 scribing witnesses.

LEE S. BURRIDGE.
